UNITED STATES PATENT OFFICE.

LOUIS D. NADEL, OF NEWARK, NEW JERSEY, ASSIGNOR, BY MESNE ASSIGNMENTS, TO HARRIMAN NATIONAL BANK OF THE CITY OF NEW YORK, TRUSTEE.

TONE-ARM.

1,394,509.

Specification of Letters Patent.

Patented Oct. 18, 1921.

Application filed January 23, 1919. Serial No. 272,681.

To all whom it may concern:

Be it known that I, LOUIS D. NADEL, a citizen of the United States, and a resident of Newark, in the county of Essex and State 5 of New Jersey, have invented a certain new and useful Tone-Arm, of which the following is a specification.

My invention relates to tone-arms for talking machines, and more particularly to that 10 type of device which is pivoted to the talking machine cabinet whereby it is movable laterally, with respect to the axis of the turn-table, and which is provided with a pivoted portion carrying the sound-box, and which 15 portion is movable in the plane of the axis of the turn-table whereby the sound-box may be moved toward and away from the record disk carried by the turn-table and which may be locked against movement when in the latter position.

The objects of my invention are to provide a tone-arm of the character described which will be simple in construction, effective in operation, not likely to get out of order, and in which the sound-box will be positively locked in the inoperative position and cannot be accidentally released, and which is inexpensive to manufacture.

With these and other objects in view to 30 be more fully set forth hereinafter, the invention consists in the novel construction, combination of elements, and arrangement of parts which will be exemplified in the operation and construction hereinafter described in the specification and illustrated in the accompanying drawings considered together or separately.

In tone-arms of the character described, with which I am familiar, the relatively 40 movable member of the tone-arm is secured in its inoperative position, away from the turn-table by friction devices and the movable member is moved to operative position by pressure applied to the sound-box.

With the type of tone-arm just above described, there is always danger that when force is applied to release the member, the stylus will be forcibly brought into contact with the record thereby causing injury to 45 the record and to the stylus.

With my improved tone-arm, two movements are necessary to release the lock and the member must be firmly grasped by the hand in order to effect the unlocking. When

the unlocking is accomplished the stylus 55 can be gently lowered into contact with the record without danger of injury to the record, sound-box or stylus.

The invention will be first described in connection with the accompanying drawings, illustrating one embodiment of the invention, wherein similar reference characters are used to designate corresponding parts throughout the several views, and then more specifically defined and indicated in 65 the appended claims.

Figure 1 is a side elevation, partly in section, of a tone-arm embodying my invention;

Fig. 2 is a detail sectional view taken on 70 the line 2-2 of Fig. 1; and

Fig. 3 is a detail bottom plan view of the co-acting elements of the tone-arm.

In carrying out my invention, I provide a tone-arm member 1 of any desired construction and configuration. The tone-arm is adapted to be pivoted to the top of the motor board of a cabinet in such a manner that it may be swung over the turn-table in the plane of the turn-table as is common. The 80 tone-arm member may be tapered from the base 2 to the free end 3 thereof. It may decrease in diameter from end to end by means of steps, or its diameter may be reduced from the base 2 to the free end 3 by a combination of tapered and stepped portions.

In the free end 3 is pivoted an elbow 4 carrying at its outer extremity a sound-box 5 having a reproducing stylus 6. The diameter of the elbow is less than that of the 90 free end 3 of the tone-arm member 1 and that portion which engages within the member 1 is spherical in order to fill the end of the member. A screw 7 passes through the member 1 and the spherical portion of the 95 elbow 4 whereby the latter is pivoted so as to be capable of pivotal movement perpendicular to the horizontal axis of the member 1.

A pin 8 is loosely carried in the walls of 100 the elbow in proximity to the spherical portion. The pin has a reduced extremity 9 at one end thereof and a peripheral groove 10 at or near its center. The pin may be readily removed from the elbow through the perforation 11 with which that portion of the pin 105 having the greatest diameter engages. The pin cannot be removed from its position by

movement in the opposite direction for the reason that the body of the pin cannot be passed through the perforation 12 with which the reduced extremity 9 of the pin engages.

Engaging the groove 10 of the pin 8 is the forked extremity of a trigger 13 which extends toward the open end of the elbow. A finger piece 14 projects from the under side 10 of the trigger and extends through a slot 15 in the under side of the elbow.

The free extremity of the trigger 13 is provided with a downwardly inclined spur 16 which passes through a notch 17 in the under side of the free end of the elbow. The free end of the tone-arm member 1 is provided with a notch 18 in its lower wall and in line with the notch 17 and the spur 16. A spring 19 is wound around the pin 8 20 and one extremity of the spring engages the upper wall of the elbow and the other end of the spring bears down on the trigger and retains the latter in position with the finger piece 14 in the slot 15 and the spur 16 in engagement with the notch 17.

The operation is as follows:—

The device is shown in operative position in full lines in Fig. 1, with the stylus resting in a record groove in the record disk 30 which is supported on the turntable. The engagement of the stylus with the record is by gravity. It will be noted that the sound-box and stylus may assume a position lower than that shown in full lines.

35 When it is desired to raise the sound-box for the purpose of changing the record, renewing the stylus, or for any other reason, the sound-box is grasped by the hand and raised to the position shown in dotted lines in Fig. 1. The spring 19 will be deflected by the engagement of the spur 16 with the lower wall of the member 1 and when the elbow reaches the position shown in dotted lines the spur will be snapped into the 45 notch 18 and the elbow will be firmly locked against downward movement.

Both hands of the operator will now be free to change the record or needle, and no amount of force exerted in the downward 50 direction will move the elbow.

When it is desired to move the sound-box to playing position, the elbow or sound-box is grasped by the hand. One finger of the hand grasping the member is brought into 55 engagement with the roughened exposed end of the finger piece 14. Pressure of the finger against the finger piece will not release the spur from the notch 18 but the elbow 4 must be raised an extent sufficient to permit the 60 extremity of the spur 16 to pass the base of the notch 18 when the trigger 13 is caused to pivot on the pin 8 by the pressure on the finger piece 14. When the spur is released from the notch 18 the sound-box may be 65 lowered to bring the stylus into engagement

with the record. The screw 7 on which the elbow 4 is pivoted acts as a stop to prevent excessive movement of the trigger which latter will engage the screw before the spur 16 can be moved out of the notch 17. The engagement of the spur in the notch 17, and the piece 14 in the slot 15, will retain the trigger in the center of the elbow and the engagement of the forked end of the trigger with the groove in the pin 8 will prevent 75 withdrawal of the latter.

If, for any reason, it becomes necessary to remove the trigger or the spring 19, the screw 7 is removed and the elbow 4 is separated from the member 1. The trigger may 80 now be moved upward until the spur and finger piece are disengaged from the notch and slot respectively. The jaws are withdrawn from engagement with the groove 10. The trigger may be removed through the 85 open end of the elbow, the pin withdrawn through the hole, and the spring will fall out of the elbow. To reassemble the parts the operation just above described is reversed.

90 In accordance with the provisions of the patent statutes, I have described the principle of my invention together with the apparatus which I now consider to represent the best embodiment thereof, but I desire it 95 understood that my invention is not confined to the particular form of apparatus herein shown and described, and, therefore, I claim broadly the right to employ all equivalent instrumentalities coming within the scope 100 of the appended claims, and by means of which objects of my invention are attained, and the new results accomplished, as herein set forth, as it is obvious that the particular 105 embodiments herein shown and described are only illustrative of some that can be employed to attain these objects and accomplish these results.

Having now described my invention, what I claim and desire to secure by Letters Patent is:—

110 1. A tone-arm comprising a tubular member, a tubular element pivoted in the member and capable of pivotal movement in the direction perpendicular to the line of the axis 115 of the member, a pin carried by the element, a trigger pivoted to the pin, a portion of said trigger projecting through a wall of the element, there being a notch in the member for engagement with the trigger, and a stop 120 for limiting the pivotal movement of the trigger.

125 2. A tone-arm comprising a tubular member, a tubular element pivoted in the member and capable of pivotal movement in the 130 direction perpendicular to the line of the axis of the member, a pin carried by the element, a trigger pivoted to the pin, there being a slot in the element, a portion of said trigger projecting through a slot, there be-

ing a notch in the member for engagement with the trigger, and a stop for limiting the pivotal movement of the trigger.

3. A tone-arm comprising a tubular member, a tubular element pivoted in the member and capable of pivotal movement in the direction perpendicular to the line of the axis of the member, a pin carried by the element, a trigger pivoted to the pin, there being a slot in the element, a portion of said trigger projecting through the slot, there being a notch in the member for engagement with the trigger, a stop for limiting the pivotal movement of the trigger, and a spring 10 for maintaining the portion in the slot.
4. A tone-arm comprising a tubular member, a tubular element pivoted in the member and capable of pivotal movement in the direction perpendicular to the line of the 20 axis of the member, a pin loosely carried by the element, a groove in the pin, a trigger, said trigger having a notch engaging the groove in the pin, a finger piece carried by the trigger, there being a slot in the element through which the finger piece projects, 25 there being a notch in the extremity of the element, a spur on the trigger for engagement with the notch, the extremity of the member having a notch for engagement of the spur to lock the element to the member, a spring engaging the trigger and the element, the pivot connecting the element to the member forming a stop to limit the movement of the trigger.

This specification signed and witnessed 35
this 2nd day of January, 1919.
